CENTRIFUGAL PUMP

Charles Erb Wuensch, Saratoga, Calif.

Application June 5, 1944, Serial No. 538,793

3 Claims. (Cl. 103—114)

The present invention relates to centrifugal pumps, and particularly to centrifugal pumps which are principally employed in pumping sand, grit and other abrasive material both by pressure feed and by suction.

The conventional centrifugal pump engaged in the pumping of grit and other forms of abrasive and granular material rapidly decreases in pumping efficiency during operation due to the constant wear of the abrasive particles on the several parts of the pump. This requires constant maintenance and the stopping of the pumping operation until repairs and replacements can be made. The frequency of such shutdowns either brings about a substantial investment in an abnormal amount of replacement pumps and parts or an inordinate waste of time due to the frequency of the stops. In the pumps heretofore known and used it is the unfailing experience that when wear once begins it becomes increasingly greater and more rapid with a consequent increase of inefficiency in the operation until complete shutdown is required.

Among the objects of the present invention is to minimize the wear in centrifugal pumps caused by pumping abrasive and other substances in suspension.

It is also an object to provide a centrifugal pumping device where the minimum initial clearance between the impeller and the enclosing casing can be maintained and regulated throughout the entire life of the pump.

Another object is to reduce the first cost and maintenance of centrifugal pumps and increase their efficiency under the abusive condition of their normal operation.

Another object is to provide a centrifugal pump which because of the regulated clearance between the impeller and its enclosing casing, delivers a larger volume than any standard centrifugal pump of equal size running under the same or similar conditions.

Another object of the present invention is to protect the pump mechanism from injury by pebbles and other large objects traveling in the flow of the material being pumped.

Still another object of the invention is to provide a pump mechanism which will resist abrasion to a greater extent than any prior pump and in which replacements take less time to install and are much less costly.

Such other objects as may become apparent as this description proceeds or which are inherently included in the device, are within its capabilities and contemplated herein.

The invention resides in the combination and construction of parts illustrated in the accompanying two sheets of drawings which show the device in a preferred embodiment. It is understood that the drawings are illustrative only and that the invention is capable of modification and change of construction without departing from the spirit or the scope of the invention and that such changes are within the present purview.

10 In the two sheets of drawings:

Figure 1 is a vertical section of a pump constructed in accordance with this invention, taken on the line I—I of Figure 2.

15 Figure 2 is a side elevation of the same, partially broken away to disclose the underlying structure.

20 Referring now more in detail to the drawings, the structure illustrated, referring first to Figure 1, comprises the base 1, supporting the cylindrical case 2 having the tangential outlet 3. The side plates 4 and 5 are bolted to the case, as at 6, 7 to complete the enclosing casing. The plate 4 has the axial suction or feed inlet 8 with the annular flange 9 bolted to the side plate 4 at 10. The case 2 has a bowl liner 11 bolted thereto at intervals, as at 12. The bowl liner 11 is preferably of rubber composition or some other elastic or resilient material. The inner periphery of this liner is preferably arcuate in cross section, as indicated at 13.

25 The base 1 has a pair of spaced pillars 14 supporting bearing housings 15, only one pillar being shown in the drawings. The driven shaft 16 is mounted with suitable bearings in the housings 15, and the driving pulley (not shown), is keyed to shaft 16 between the two bearings 15. It is to be understood that any suitable means for driving shaft 16 may be used.

30 The impeller hub 17 is fixed to the end of the shaft 16 within the casing. Impeller blades 18 are attached to the hub 17 in any suitable manner calculated to keep them in place during operation and at the same time permit them to be removed readily in case of repair or replacement. While 35 the blades are held rigidly in position they are in fact flexible so as to be free to react both to centrifugal force and to yield to permit larger particles to pass through without stopping the pumping action. The blades 18 are shown to extend

40 radially from the hub 17 to proximity with the elastic or resilient bowl liner 11 but they may also be placed tangentially. It is to be understood that their construction and the degree of flexibility will vary in accordance with the nature of the 45 material to be pumped although the structure de-

scribed herein is capable of handling all conditions normally encountered.

The impeller blades are preferably constructed in accordance with the disclosure of a pending application filed June 5, 1944, and serially numbered 538,794. For general all around work good results have been obtained from an impeller having a central internal support 19 (see Figure 2) around which is molded or shaped the impeller blades designated 18. Tough rubber or any other suitable resilient material may be molded around the central support to form the blades 18. The central support 19 may be formed with a transverse head 20 for keying and maintaining the same in the hub 17. In such event the hub 17 will have suitable slots for accepting the keys 20. It may also be formed tapering to the outer end as shown in Figure 2 which will provide graduated flexibility. Beyond the end of the reinforcing blades 18 yield more readily to the flexing force of rotation—see dotted line position—neutralizing to some extent the centrifugal force acting through the blades. The outer ends of the blades may be weighted in any suitable manner as at 19a. The purpose of weighting the outer ends is to give rigidity to the outer ends of the blades and also to stretch the blades slightly so as to minimize any tendency through centrifugal action to become larger in cross sectional diameter or area at the point of maximum flexure. It may be desirable to place holes 21 through the central support 19 in order to key the molding composition forming the resilient blades 18, through the central support 19.

The impeller blades 18 operate between two lateral resilient or flexible diaphragms 24 and 25 alike in contour and section, each having axial tubular necks 26 and 27, with lateral outwardly extending flanges 28 and 29 thereon, and peripheral collars 26a and 27a with outwardly extending flanges 30 and 31 respectively. The flange 28 is interposed between the flange 9 of the feed inlet and the side plate 4 and also flange 30 is interposed between side plate 4 and the cylindrical cover plate 2. In each instance the diaphragm flanges act as a gasket between the two holding members. On the opposite side the flange 29 is held between the side plate 5 and the flat packing ring 32 which is bolted to this place. The peripheral flange 31 acts as a gasket between the side plate 5 and the cylindrical case 2 in a similar manner as above described. These resilient lateral diaphragms 24 and 25 thus completely seal the casing joints against leakage and excessive wear and together with the liner 11 define a chamber in which the impeller operates. The diaphragms 24 and 25 form the side walls of the pumping chamber providing scant clearance for the blades 18 and the inner liner 11 provides the cylindrical wall just beyond the ends of the blades.

The spaces between the diaphragms 24 and 25 and the respective side plates 4 and 5 form expansion chambers 33 and 34 which are interconnected by the bypass pipe 35 for equalizing the pressures in the two chambers. A hand pump 36, or any other suitable device or connection, is connected to this pipe and supplies either air or hydraulic pressure to expand the chambers 33 and 34 inwardly toward the impeller blades to regulate the clearance, the pressure being indicated by the gauge 38. The diaphragms are expanded until the gauges show but minor fluctuations. A stop or check valve 37 is provided in the line and may if necessary be used to release the pressure in the chambers 33 and 34. Instead

of the pressure gauge 38, a Y tube filled with mercury may be used to indicate the proper inflation of the diaphragms.

Since the sealing device used is also the subject matter of a co-pending application it will only be briefly described here. The ring or washer 32 encircling the shaft 16 provides opposed flat surfaces for sealing the casing where the shaft passes through it into the pumping chamber. The rotating seal includes a threaded sleeve 38 having an inner flange 39, which is keyed to the shaft 16 adjacent the hub 17. Resilient annular sealing rings 40 and 41 have lips bearing against the opposite sides of the stationary ring 32. The locking rings 42 and 43 are threaded on the sleeve 38 and bear against the inner sides of the sealing rings 40 and 41 respectively. The stiff expansive spring 47 encircles the sleeve 38 between the locking rings 42 and 43 to frictionally prevent them from backing away from the sealing rings 40 and 41 respectively. The external running nut 45 is threaded on the outer end of the sleeve and fixed to the shaft 16 by the set screw 46. This form of packing is highly efficient and operates with the minimum of friction against the ring 32. The rotation of the ring 40 tends to throw gritty particles away from the contact with the sealing ring. The space between the rings 40 and 41 is kept filled with grease or water by the compression drip cup 48.

This invention operates substantially as follows: the pumped material entering the inlet 8, is driven outward by the impeller blades 18 against the liner 11 of the case and between the diaphragms 24 and 25 until the volume builds up and then it is forced through the outlet 3. The diaphragms 24 and 25 are deflected inwardly into approximate or actual contact with the sides of the impeller blades 18 by the pressure within the chambers 33 and 34 by means of the hand pump 36. Any degree of clearance may be maintained by adjusting the pressure in chambers 33 and 34. The pressure output from the casing can be increased by increasing the pressure within the chambers 33 and 34 until the diaphragms 24 and 25 bear lightly against the sides of the impeller blades 18, preventing backslip in the centrifugal output. These are features particularly valuable in centrifugal pumping.

In pumping sand, gravel and waste waters there are occasional obstructive bodies such as rocks and flotsam that would injure and stop the conventional pumps having rigid clearances. In the present invention the diaphragms 24 and 25 and the flexible impeller blades 18 yield clearance and permit the obstructive object to pass.

A useful feature of the present device is the ease with which repairs and replacements can be made. The diaphragms 24 and 25 may be removed, as well as the cylindrical liner 11, by removing the side plate 4, loosening the opposite side plate 5, and removing the individual impeller blades 18.

It is to be understood that in maintaining the pressure against the diaphragms 24 and 25 any suitable automatic means may be substituted for the hand pump. The automatic means may be set to maintain any predetermined pressure or series of pressures.

I claim:

1. A centrifugal pump comprising in combination a case having side plates forming an enclosing casing with inlet and outlet openings, an impeller in said casing between said openings, resilient diaphragms interposed between said covers

and forming pressure chambers on the opposite sides of said impeller, and means for varying the pressure in said chambers to deflect said diaphragms relative to said impeller.

2. A centrifugal pump comprising in combination, a case having a resilient interliner and opposed cover plates forming an enclosing casing with inlet and outlet openings, an impeller in said casing between said openings, flexible diaphragms having their peripheries interposed between said case and covers respectively and forming pressure chambers on the opposite sides of said impeller, means for interconnecting said pressure chambers, and means for varying the pressure in said chambers for deflecting said diaphragms relative to said impeller.

3. A centrifugal pump comprising in combination, a case having a central inlet opening and

an outlet opening including side plates fixed to the opposite sides of said case and a resilient peripheral inner liner therebetween, an impeller between said plates and having a shaft projecting through one of said side plates, flexible diaphragms having peripheral flanges for holding said diaphragms in place within the case and acting as gaskets therefor, interconnecting pressure chambers between said diaphragms and said side plates, a flat packing ring encircling said shaft and fixed to said casing, a pair of sealing rings fixed on said shaft and bearing against the opposite sides of said packing ring, and means for introducing pressure into the pressure chambers between said side plates and said diaphragms, and means for automatically maintaining the same.

CHARLES ERB WUENSCH.
